HYDRAULIC JACK

Myndert Geesink, Weesp, Netherlands; Marretje Gijsbertha Geesink-de Graaf, Gijsbertus van den Burg, Catharina Jacoba van den Burg-Geesink, Aaltje Gerarda Bokelmann-Geesink, Reinhard Frederik Hendrik Bokelmann, Arnolda Catharina Magdalena Geesink, and Myndert Marten Geesink, sole heirs of the estate of Myndert Geesink, deceased

Application August 13, 1947, Serial No. 768,463
In the Netherlands August 15, 1946

9 Claims. (Cl. 121—40)

1

This invention relates to jacks and more particularly to fluid operated jacks.

It is the principal object of the present invention to provide a fluid operated jack with mechanically operative locking means for locking the jack in selected operative position.

It is another object of the invention to provide a fluid operated jack with locking means which has simplicity of assembly, economy of construction and efficiency in operation.

The novel features that are considered characteristic of the invention are set forth with particularity in the appended claims. The invention itself, however, both as to its organization and its method of operation will best be understood from the following description of specific embodiments when read in connection with the accompanying drawing, wherein like reference characters indicate like parts and in which:

Figure 1 is a cross-sectional view taken axially through a jack in accordance with the present invention, and

Figure 2 is a fragmentary cross-sectional view similar to Figure 1 but illustrating a modification.

Referring now to the drawing, specifically to Figure 1, a jack in accordance with the present invention comprises a cylinder 1 having a piston 2 slidable therein. A hollow rod 3 is carried by said piston and extends through one end closure of said cylinder 1. An eye 4 or the like is fixed on the outer end of said piston rod 3 for engaging the part to be jacked up or moved and when so engaged the eye 4 retains the rod 3 and piston 2 against rotation.

A screw spindle 5 is mounted in the opposite end of the cylinder 1 and passes through and threadedly engages an internally threaded bore centrally in the piston 2 and telescopes in the hollow rod 3. The threaded engagement between the spindle and the piston is non-self-locking so that relative axial movement between said piston and spindle is readily effective and will result in relative rotational movement due to said threaded engagement.

The spindle 5 has a brake disc 6 mounted thereon below the piston 2 and retained in fixed relation thereto by a key or the like 6'. The lower end of the cylinder 1 is closed by a brake drum 7 which is cooperative with said disc 6 and the spindle 5 extends through and is rotatable in said drum. The spindle 5 has a collar 8 below the drum which permits limited axial movement of said spindle to accommodate relative movement between said brake disc 6 and brake drum 7. A thrust bearing 9 is mounted beneath the

2

drum 7 for engagement by said collar 8 when the spindle is lifted and precludes excessive friction on the collar 8 that would inhibit rotation of the spindle.

5 A fluid passage opening 10 is provided in the cylinder 1 immediately above the drum 7 and below the piston 2. The brake disc 6 is provided with a port 11 for passage of fluid to both sides thereof and thereby to equalize the pressure thereon and prevent development of vacuum that would hold said disc 6 in braking engagement with said drum 7. The lower end of the spindle 5 extends into a supplementary cylinder 12 on the lower end of the cylinder 1 and a plunger 13 slidable in said supplementary cylinder is connected with said spindle.

In operation, the jack is positioned with the eye 4 engaging the part to be lifted or moved and fluid under pressure is then admitted 20 through the opening 10 into the cylinder 1. The pressure of the fluid causes axial displacement of the piston 2 with its rod 3 and eye 4. This displacement initially causes the limited axial movement of the spindle 5 that is permitted by the collar 8 to disengage the brake disc 6 from the brake drum 7 and subsequent piston displacement merely causes rotation of the spindle 5 due to the threaded engagement therebetween.

When the piston has been displaced sufficiently 30 to lift or move the part the desired distance, the admission of fluid to the cylinder 1 is stopped. The pressure or load of the part on the eye 4 will cause the piston to move in the opposite direction and this movement will be transmitted to the spindle 5 to the extent permitted by engagement between the brake disc 6 and drum 7 which will prevent both axial and rotational movement of the spindle 5.

As the spindle is then held against rotation 40 by the brake, the piston 2 will be locked by the threaded engagement with the spindle against further axial displacement as long as the pressure of the part is maintained against the eye 4 so as to preclude rotation of the piston and consequent threading thereof along the spindle. When it is desired to release the jack, the spindle 5 is lifted by admission of fluid under pressure into the supplementary cylinder 12 and against the plunger 13. This lifting of the spindle disengages the brake disc 6 from the drum 7 and permits rotation of the spindle. Simultaneously, the fluid pressure is released in the cylinder 1 so that the piston can be depressed while the spindle 5 is caused to idly rotate by the threaded 50 connection therebetween.

Obviously, a mechanically operated release may be substituted for the fluid operated release of the supplementary cylinder 12 and plunger 13. A suitable mechanical release is shown, by way of example, in Fig. 2. In this case, the lower end of the spindle 5 extends beyond the lower end closure of the cylinder 1 and the end of said spindle is engageable by an eccentric or cam 14 that is operable by a crank or lever 15. In other respects the structure is identical to that shown in Figure 1.

Although certain specific embodiments of the invention have been shown and described, it is obvious that many modifications thereof are possible. The invention, therefore, is not to be restricted except insofar as is necessitated by the spirit of the appended claims.

What I claim is:

1. In a hydraulic jack for non-rotatable loads, in combination, a cylinder; a piston fitting therein and axially movable therein; means for supporting the load on said piston; means for admitting fluid under pressure to said cylinder so as to impart movement to said piston; said piston having an axial opening; a non-selflocking screw thread provided about said opening; a non-selflocking screw spindle extending through said opening and being engaged by said screw thread, the said spindle being capable of limited axial movement relative to said cylinder under the weight of the load; locking means cooperative between said spindle and said cylinder for locking said spindle against rotation, the said locking means being operated upon axial movement of said spindle; and means for moving said spindle to release said locking means.

2. In a hydraulic jack for non-rotatable loads, in combination, a cylinder; a piston fitting therein and axially movable therein; means for supporting the load on said piston; means for admitting fluid under pressure to said cylinder so as to impart movement to said piston; said piston having an axial opening; a non-selflocking screw thread provided about said opening; a non-selflocking screw spindle extending through said opening and being engaged by said screw thread, the said spindle being capable of limited axial movement relative to said cylinder under the weight of the load; locking means cooperative between said spindle and said cylinder for locking said spindle against rotation, the said locking means being operated upon axial movement of said spindle; and means operated by fluid under pressure for moving said spindle to release locking means.

3. In a hydraulic jack for non-rotatable loads, in combination, a cylinder; a piston fitting therein and axially movable therein; means for supporting the load on said piston; means for admitting fluid under pressure to said cylinder so as to impart movement to said piston; said piston having an axial opening; a non-selflocking screw thread provided about said opening; a non-selflocking screw spindle extending through said opening and being engaged by said screw thread, the said spindle being capable of limited axial movement relative to said cylinder under the weight of the load; locking means cooperative between said spindle and said cylinder for locking said spindle against rotation, the said locking means being operated upon axial movement of said spindle in one direction; a movable abutment; and means for engaging said spindle by said abutment so as to impart axial movement to

said spindle in the opposite axial direction so as to release said locking means.

4. In a hydraulic jack for non-rotatable loads, in combination, a cylinder; a piston fitting therein and axially movable therein; means for supporting the load on said piston; means for admitting fluid under pressure to said cylinder so as to impart movement to said piston; said piston having an axial opening; a non-selflocking screw thread provided about said opening; a non-selflocking screw spindle extending through said opening and being engaged by said screw thread, the said spindle being capable of limited axial movement relative to said cylinder under the weight of the load; cooperating wedge elements associated with said spindle and said cylinder for locking said spindle against rotation when forced together by axial movement of said spindle in one axial direction; and means for forcing said spindle in the opposite axial direction so as to disengage said wedge elements.

5. In a hydraulic jack for non-rotatable loads, in combination, a cylinder; a piston fitting therein and axially movable therein; means for supporting the load on said piston; means for admitting fluid under pressure to said cylinder so as to impart movement to said piston; said piston having an axial opening; a non-selflocking screw thread provided about said opening; a non-selflocking screw spindle extending through said opening and being engaged by said screw thread, the said spindle being capable of limited axial movement relative to said cylinder under the weight of the load; cooperating wedge elements associated with said spindle and said cylinder for locking said spindle against rotation when forced together by axial movement of said spindle in one axial direction; and means operated by fluid under pressure for forcing said spindle in the opposite axial direction so as to disengage said wedge elements.

6. In a hydraulic jack for non-rotatable loads, in combination, a cylinder; a piston fitting therein and axially movable therein; means for supporting the load on said piston; means for admitting fluid under pressure to said cylinder so as to impart movement to said piston; said piston having an axial opening; a non-selflocking screw thread provided about said opening; a non-selflocking screw spindle extending through said opening and being engaged by said screw thread, the said spindle being capable of limited axial movement relative to said cylinder under the weight of the load; cooperating wedge elements associated with said spindle and said cylinder for locking said spindle against rotation when forced together by axial movement of said spindle in one axial direction; a movable abutment; and means for engaging said spindle by said abutment so as to impart axial movement in the opposite direction thereto thereby releasing said wedge elements.

7. In a hydraulic jack for non-rotatable loads, in combination, a cylinder; a piston fitting therein and axially movable therein; means for supporting the load on said piston; means for admitting fluid under pressure to said cylinder so as to impart movement to said piston; said piston having an axial opening; a non-selflocking screw thread provided about said opening; a non-selflocking screw spindle extending through said opening and being engaged by said screw thread, the said spindle being capable of limited axial movement relative to said cylinder under the weight of the load; locking means cooperative

between said spindle and said cylinder for locking said spindle against rotation, the said locking means being operated upon axial movement of said spindle with said movement under the influence of the load operating to lock said means and said movement induced by piston movement due to the fluid pressure in the cylinder operating to release said means and separate means for moving said spindle to release said locking means.

8. In a locking device for fluid-actuated jacks for non-rotatable loads, a cylinder, a piston fitting in and axially movable in the cylinder, a hollow piston rod fixedly connected to the piston and supporting the load to hold said piston against turning, said piston having an axial internally threaded opening, a non-selflocking screw spindle loosely threaded through the axial threaded opening in the piston, held against free unlimited axial movement in the cylinder and extending loosely into the hollow piston, means to admit fluid pressure to the cylinder beneath the piston to raise the latter and load supported by the piston rod, the said spindle being capable of limited axial movement relative to said cylinder under the weight of the load, a locking portion in said cylinder locking means splined on the spindle and engageable with said locking portion for locking said spindle against rotation, said locking means being operated upon axial movement of said spindles, and means for moving said spindle to release said locking means.

9. In a hydraulic jack for non-rotatable loads, a cylinder, a piston fitting in and axially movable in the cylinder, a tubular piston rod rigidly connected to the piston and extending from the cylinder for connection to and supporting the load to hold said piston against rotation, means for admitting fluid under pressure to said cylinder so as to impart axial movement to said

5 piston, said piston having an axial internally threaded opening a non-selflocking coarse thread screw spindle loosely rotatably engaged through the axial threaded opening in the piston and movably extending loosely into the tubular piston rod, means between the spindle and cylinder beneath the piston to hold the spindle against unlimited axial movement but allowing limited downward axial movement of said spindle under the weight of the load, a locking ring held in the cylinder around the spindle beneath the piston, a friction braking member on the lower portion of the spindle and operatively engageable with the ring upon downward movement of the spindle to hold the spindle against rotation, an extension on the spindle extending through and below the lower end of the cylinder, and means acting on the lower end of the extension to lift the braking member away from the ring to release same to permit rotation of the spindle and raising of the piston under the influence of the fluid under pressure or lowering thereof when the pressure is released.
